APPARATUS FOR PICKLING COILS

Charles G. Watson, Youngstown, Ohio, assignor
to The Youngstown Welding & Engineering
Company, Youngstown, Ohio, a corporation of
Ohio

Application March 24, 1948, Serial No. 16,838

3 Claims. (Cl. 134—57)

1

This invention relates to an apparatus for pickling loosely coiled metallic material such as strip steel, wire or the like.

In the course of manufacture of strip steel, or other relatively long metallic material, the material can be coiled in relatively open or loose flat spiral configurations; or in the case of strip steel, it can be coiled tight and "back spun" to open up the coil loops. It is, however, difficult to remove grease, scale or other deleterious substances from such material when in coiled form and, in particular, it is very difficult to properly pickle strip steel, or the like when thus coiled. This is due primarily to the fact that conventional pickling methods and apparatuses do not provide sufficient movement of the convolutions of the coils relative to each other so that the scale or other substances thereon is not properly loosened and the pickling solution does not properly penetrate between the convolutions. Moreover, conventional procedures and apparatuses do not cause sufficient bodily movement of the coils in the pickling solution with the result that a considerable portion of the scale or other deleterious substances which is loosened is still retained within the convolutions.

An object of the invention is to provide a novel and improved apparatus for treating, for example, pickling, loosely coiled metallic material, wherein the coil is immersed in a treating solution and repeatedly raised and lowered therein and rotated while immersed.

Another object of the invention is to provide a novel and improved apparatus for treating loosely coiled metallic material such as strip steel, wire or the like, which comprises repeatedly varying the radial separation between different portions of the convolutions of the coil while immersed in a treating solution and also partially rotating the coil while so immersed.

A further object of the invention is to provide a novel and improved apparatus for pickling loosely coiled strip steel, wire or the like, wherein the coil is repeatedly raised and lowered and the weight of the coil utilized to assist in effecting repeated variations in the radial separation between different portions of the convolutions of the coil while immersed in a pickling solution and also in partially bodily rotating the coil and/or circumferentially displacing the convolutions relative to each other while the coil is immersed and in alternation with the variations in the radial separation of the convolutions.

The invention further resides in certain novel features of construction and combination, and

2

arrangement of parts of an apparatus, and further objects and advantages thereof will be apparent to those skilled in the art to which it pertains from the following description of the present preferred embodiment described with reference to the accompanying drawings in which similar reference characters designate corresponding parts in the several views and in which:

Fig. 1 is a top plan view of a novel apparatus constructed in accordance with this invention;

Fig. 2 is a longitudinal sectional view taken substantially on the section line 2—2 of Fig. 1;

Fig. 3 is a transverse sectional view taken on the section line 3—3 of Fig. 1 and showing one of the coils to be treated in its uppermost position within the pickling tank;

Fig. 4 is a sectional view similar to Fig. 3 but showing the coil of material being treated in its lowermost position in the tank;

Fig. 5 is a sectional view taken substantially on the section line 5—5 of Fig. 1; and

Fig. 6 is a schematic wiring diagram of a suitable electric circuit for controlling operation of the motor for the apparatus.

25 The apparatus of this invention is capable of being used to subject loosely coiled metallic material, such as strip steel or the like, to treatment by a variety of different solutions. For the sake of conciseness and definiteness, however, the novel apparatus is hereinafter specifically described as used to pickle loose spiral coils of strip metal. This restriction of the description is, however, only for the purpose of illustrating one practical embodiment and is not to be considered as limiting the invention to such a use.

30 As shown in the drawings, the present preferred apparatus comprises a pickling tank generally designated 10 which may be formed of any suitable material and is adapted to contain a pickling solution. Adjacent one side of the tank are spaced stands or pillars 11 and 12 which may be formed separately from the tank or as integral projections therefrom. Upon the top surface of the pillar 11 are mounted a pair of bearing brackets or supports 13 and 14 in parallel spaced relationship. A corresponding pair of bearing supports or brackets 15 and 16 are mounted in parallel spaced relationship upon the top of the pillar or stand 12. Each of the bearing supports or brackets 13, 14, 15 and 16 is provided with a substantially semi-circular bearing surface adjacent its upper forward end in which a shaft 17 is rotatably or rockably supported, which shaft is held from displacement relative to the brackets by bearing cap members 18, 19, 20 and 21 secured

to the bearing brackets 13, 14, 15 and 16, respectively, by suitable bolts such as 22.

The shaft 17 is provided with an arm 23, one end of which is fixedly connected to the shaft 17 intermediate the bearing brackets 13 and 14. A second arm 24 similar to the arm 23 is fixedly secured to the shaft 17 intermediate the bearing brackets 15 and 16. The arms 23 and 24 rock with the shaft 17, extend therefrom in substantial alignment forwardly over the tank 10, and are provided adjacent their forward ends with semi-circular recesses for removably receiving a bar 25 forming a part of a supporting means for the coils C which are to be treated. It is to be understood that one or more coils may be simultaneously treated depending upon the construction of the apparatus and the width of the coiled material. The bar 25 may be substantially circular in cross section, as shown, or may simply have cylindrical bearing surfaces formed thereon for cooperation with the semi-circular recesses in the arms 23 and 24. Depending from the lower surface of the bar 25 is a hook-like member 26 adapted to be inserted through the central opening in the coil or coils C to be treated so that the latter may be lifted and supported by the hook with their axes extending substantially horizontally and parallel with the length of the tank.

The hook 26 may be constructed in any suitable manner but is here shown as a plate having reinforcing flange members along the edges thereof, the hook 26 preferably being made of material inert to the treating solution. The bar 25 is further provided with suitable means such as loop members 27 and 28 for receiving cables or the like by which the bar, and hence the coils supported thereon, may be lifted from the tank and transported to any desired position by a crane or the like.

As previously mentioned, the shaft 17 and hence the arms 23 and 24 are repeatedly rocked in opposite directions. This may be effected by any suitable means. As illustrated in the drawings, the shaft is rocked by a reversible electric motor 29 connected to the input shaft 30 of a gear reduction unit 31, the output shaft 32 of which is connected with the shaft 17. The gear reduction unit 31 provides a large reduction of speed so that the shaft 32 moves at a relatively slow speed and is provided with a means, generally designated 34, for automatically effecting reversal of the motor 29 when the shafts 32 and 17 have been rotated through a preselected portion of a revolution so that the arms 23 and 24 are rocked through an arc of preselected size.

As shown in Fig. 5, the mechanism 34 comprises a pair of electrical switches 35 and 36 of commercial construction mounted for sequential actuation by a sector-shaped actuator, generally designated 37, which is connected to the shaft 32. Preferably, the sector-shaped actuator 37 is adjustable so that the limits and extent of arcuate movement of the shaft 32, and hence of the arms 23 and 24, may be adjusted. In the illustrated embodiment this is achieved by having the actuator 37 formed of two sector-shaped members 38 and 39 each adjustably fixed to the shaft 32 by set screws. In addition, the members may be provided with cooperating arcuate slots for the reception of a connecting bolt 40. The members 38 and 39 may be angularly adjusted relative to each other and/or the shaft 32 to vary the extent and/or limits of the angular movement of shaft 32, which in turn determines the extent of and the limits to which the arms 23 and

24 are rocked. Further adjustment of the angular movement of the shaft 32 may be effected by adjusting the bracket members 41 and 42, upon which the switch members 35 and 36 are mounted, relative to the housing of the unit 34. For this purpose the switch mounting brackets are provided with slots through which the mounting screws 43, 44, respectively, pass. The switches 35 and 36 are provided with pivoted actuating arms 45 and 46, respectively, adapted to be contacted alternately by the sector-shaped actuator 37 to momentarily close their normally open contacts.

The electric motor 29 shown is of the three-phase, alternating current, reversible type and the energization thereof for rotation in opposite direction is under the control of the switches 35 and 36. This is effected by connecting a source of three-phase electrical power, represented by the wires L1, L2 and L3, to one set of contacts of a circuit breaker 50, the other contacts of which are respectively connected with wires 47, 48 and 49 on the machine side of the circuit. The wire 47 is connectible to one lead of the motor 29, either through the normally open contact 52a of a relay 52 and a wire 47a, or through a wire 47b and the normally open contact 56a of a relay 56. The wire 48 is connectible with a second lead 51 of the motor through a normally open contact 52b of the relay 52. The wire 49 is connectible with the third lead 53 of the motor 29 through the normally open contact 52c of relay 52. One end of a wire 54 is connected with the wire 48 at a point between the circuit breaker 50 and the contact 52b, the other end of this wire being connectible with one end of wire 55 through the normally open contact 56b of the relay 56, the other end of the wire 55 being connected with the motor lead 53. A wire 51 is connected at one end with the wire 49 between circuit breaker 50 and the contact 52c, the other end of this wire 51 being connectible to the motor lead 51 through the normally open contact 56c of relay 56 and a wire 58. Consequently, when the circuit breaker 50 is closed and the relay 52 is energized while relay 56 is deenergized, the motor 29 is energized for rotation in one direction through the leads 47, 51 and 53 and the now closed contacts 52a, 52b and 52c. When relay 52 is deenergized and relay 56 is energized, the motor is then energized for rotation in the reverse direction since the contacts 52a, 52b and 52c are now open and the contacts 56a, 56b and 56c are closed with the result that the motor leads 51 and 53 are, in effect, reversed by the now closed contacts 56b and 56c. The energization of the relays 52 and 56 are under control of the switches 36 and 35, respectively, so that the motor 29 rotates in one direction until the actuator 37 operates one of these switches at which time the motor is reversed and operates in the reverse direction until the actuator engages the other of the switches. This reversing action continues as long as the apparatus is in operation.

In order that the motor circuit will remain closed after the actuator 37 has moved from engagement with the operating arm of one of the switches 35, 36 and until the said actuator engages the operating arm of the other of these switches, the relays 52 and 56 are each provided with additional contacts for controlling holding circuits for the relays. Thus relay 52 is provided with a normally open contact 52d, adapted to engage and bridge stationary contacts 59 and 60,

and this relay also has a normally closed contact 52e which engages and bridges the stationary contacts 61 and 62. The relay 56 is provided with a normally closed contact 56d bridging stationary contacts 63 and 64, and this relay also has a normally open contact 56e adapted to engage and bridge stationary contacts 65 and 66.

A wire 67 connects the wire 48 with a wire 68 through the normally closed movable contact of a push-button type stop switch 69. The wire 68 is adapted to be momentarily connected with a wire 70 through the normally open contact of a push-button type start switch 71. This wire 70 is connected with a wire 72 which interconnects the contacts 60 and 63 and, in addition, the wire 70 is connected to one terminal 73 of the coil of a relay 74. The other terminal of relay 74 is connected to the wire 47 by a wire 75, the latter also being connected to one terminal 76 of the coil of relay 52 and to the corresponding terminal of the coil of relay 56 by means of a wire 77. The other terminal 78 of the coil of relay 56 is connected to the contact 66 by a wire 79 while the second terminal 80 of the coil of relay 52 is connected to the contact 64 by a wire 81. The relay 74 is provided with two normally open contacts 74a and 74b adapted to respectively engage and bridge stationary contacts 82, 83 and 84, 85. The contacts 82 and 84 are connected together and to the wire 68 by means of a wire 86. The contact 83 is connected to the previously mentioned wire 70 while the contact 85 is connected with a wire 87 which is in turn connected to the stationary contacts 59, 61 and to the stationary contact of switch 35. The movable contact of switch 35 is connected to the wire 79, which is in turn connected with the terminal 78 of the coil of relay 56. The movable contact of switch 36 is connected with the wire 87, the stationary contact of this switch being connected with the wire 81 and hence with the terminal 80 of the coil of relay 52. The contacts 62 and 65 are interconnected by a wire 88.

The circuit just described is such that, when the circuit breaker 50 is closed, the motor 29 is placed in operation by momentarily depressing the start button 71. This closes a circuit through the coil of relay 74 energizing the latter and thereby closing the normally open contacts 74a and 74b. A holding circuit for relay 74 is thus provided by the now closed contact 74a so that the relay 74 is held energized until the stop button 69 is actuated.

The momentary closing of start switch 71 also provides an energizing circuit for the coil of relay 52, through stop switch 69, start switch 71, wires 10, 72 and the normally closed contact 56d. Consequently, relay 52 now closes its normally open contacts 52a, 52b, 52c and 52d and opens its normally closed contact 52e. Closing of the contact 52d provides a holding circuit for the relay 52 through the now closed contacts 74b, contact 52d and contact 56d. At the same time the movement of the contact 52e to open position prevents energization of the relay 56. Closing of the contacts 52a, 52b and 52c energizes the motor 29 for rotation in one direction with consequent rocking of the arms 23, 24.

Rotation of the motor and movement of the arms 23 and 24 continue in this direction until the actuator 37 engages the arm 45 of switch 35 moving the arm 45 to circuit closing position. When this occurs a circuit is completed energizing the relay 56 so that the contacts 56a, 56b, 56c and 56e of the latter are moved to closed

positions and contact 56d is moved to open position. Opening of the circuit at 56d deenergizes relay 52 so that its contacts 52a, 52b, 52c and 52d move to open positions while its contact 52e moves to circuit closing position. A holding circuit is therefore provided for the coil of relay 56, this circuit extending through the now closed contacts 52e and 56e. Opening of the contacts 52a, 52b and 52c has deenergized the motor 29 thus terminating its rotation and that of the arms 23, 24 in one direction and substantially simultaneously therewith the contacts 56a, 56b and 56c have moved to circuit closing positions thereby energizing motor 29 to rotate the latter and hence 15 rock the arms 23, 24 in the opposite direction.

Rotation of the motor and movement of the arms in this reverse direction continue until the actuator 37 engages the movable arm 46 of switch 36 moving the arm 46 to circuit closing position. 20 When this occurs a circuit is now completed through the switch 36 for again energizing the coil of relay 52. Energization of relay 52 closes its normally open contacts 52a, 52b, 52c and 52d and opens its normally closed contact 52e. The opening of the latter contact breaks the holding circuit for relay 56 deenergizing the latter so that its contacts 56a, 56b, 56c and 56e move to open positions while its contact 56d moves to circuit closing position. Closing of the contact 56d again 25 provides a holding circuit for the relay 52 through the now closed contacts 52d and 56d. Opening of the contacts 56a, 56b and 56c deenergizes the motor 29 terminating the rotation of the latter and the movement of the arms 23, 24 in the reverse direction while the substantially simultaneous closing of the contacts 52a, 52b and 52c again energizes the motor for rotation in the first direction.

The motor 29 is, therefore, repeatedly alternately energized for rotation in reverse directions for effecting rocking of the arms 23, 24 through an arc of predetermined extent, the size of this arc being determined by the adjustment of the actuator 37 and/or adjustments of the mounting brackets 41, 42 of the switches 35, 36. When the operator desires to stop rocking of the arms he simply depresses the stop button 69 thereby deenergizing relay 74 and opening its contacts 74a and 74b. Operation of the apparatus may be again initiated by momentary actuation of the start button 71.

In addition to the above described features, the apparatus shown includes spaced abutments or members 89 and 90 in the bottom of the tank 10 and extending lengthwise thereof, which members engage and support the coil or coils C in their lowermost position. The abutment 89 is higher than the abutment 90 and the inner edges of the abutments are disposed at opposite sides of the vertical diameter of the coil or coils C being treated, the upper inner edge of the abutment 89 preferably being beveled as shown. It will also be observed that the lengths of arms 23, 24 is less than one-half the width of the tank 10 so that the vertical diameter of the coil or coils C supported therein is at one side of the longitudinal center line of the tank.

The construction is such that when the coils C are supported upon the hook 26 and the arms 70 23, 24 are in their uppermost positions, as shown in Fig. 3, the upper portions of the coil convolutions are in engagement while the lower portions of the coil convolutions are radially spaced. As the arms 23, 24 rock downwardly, the coil or coils 75 C are lowered within the pickling solution and

after a slight movement the outer convolutions of the coil or coils engage the beveled surface of the abutment 89. Since this beveled surface of the abutment 89 is disposed to one side of the vertical diameter of the coil or coils, further downward movement of the arms 23, 24 causes the convolutions of the coil or coils to rotate relative to this abutment and to the hook 26, since the support afforded by the latter is progressively removed during the downward movement of the arms and the weight of the coil or coils is transferred to the abutments 89 and 90. In their lowermost positions the coils rest upon the abutments 89, 90 and are entirely or primarily supported thereby. The nature and arrangement of the abutments is such that the weight of the coil or coils has caused them to rotate slightly relative to the hook 26 and/or caused relative circumferential displacement of the convolutions with respect to each other. In addition, the upper portions of the convolutions of the coil are now radially spaced while the lower portions of the convolutions are in substantial engagement.

The extent of the relative circumferential displacement of the convolutions of the coils and/or the bodily rotation of the coil may be any desired amount depending upon the shape and spacing of the projections 89, 90 and the extent of rocking movement imparted to the arms 23, 24. That is to say, after the coil or coils have engaged the abutments 89, 90 and the hook 26 is still partially supporting the coils the convolutions thereof will have been circumferentially displaced with respect to each other but the coil or coils have not as yet bodily rotated with respect to the hook. As the rotation of the arms 23 and 24 continue and the hook 26 moves further downwardly and out of engagement with the upper portion of the inner convolution of the coil or coils C, this relative circumferential displacement of the convolutions of the coil or coils will be relieved and the coil or coils will rest upon the abutments in positions which are rotated and eccentric with respect to the position which they occupied when supported by the hook. On the other hand, the parts may be so positioned and the extent of angular rocking of the arms 23, 24 be so adjusted that the coils C are partially supported by the hook 26 even in the lowermost position of the arms 23, 24 so that while there will be circumferential displacement of the convolutions of the coil there will be little if any bodily rotation of the coil. The particular mode of operation is selected in accordance with the nature of the material being treated and the condition of that material. Consequently, where the expression "partial rotation of the coil" is employed in the appended claims, it is to be understood as including either bodily rotation of the coil or relative circumferential displacement of the convolutions of the coil, or both.

When the hook now moves upwardly again by the rocking of the arms 23, 24 in the reverse direction the radial spacing between the convolutions of the coils is again changed and the coil is lifted slightly above the abutments 89, 90. Since the hook 26 is disposed eccentrically with respect to the coil or coils C when the latter are in their lowermost position, this lifting of coils also produces a further partial rotation thereof. This varying of the radial spacing of the convolutions of the coil together with the relative circumferential displacement between the convolutions and/or partial rotation of the coil is continuously re-

peated so long as the arms 23 and 24 are rocked. The relative movement of the convolutions of the coils effectively loosens scale or other foreign substances thereon and facilitates the penetration of the pickling solution therebetween while the repeated partial bodily rotation of the coil causes the loosened scale or the like to be displaced from within the convolutions.

After the coil or coils have been sufficiently treated the motor 29 is stopped and a lifting means applied to the loops 21, 28 of the bar 25 and the latter, together with the coil or coils C suspended thereon, bodily lifted and moved to any desired point such as a rinsing tank or the like. Alternatively, the coils may be removed from the hook 26 prior to subsequent operations thereon. After the previously treated coils have been removed from the hook 26, other coils to be treated may be substituted therefor by inserting the hook 26 therethrough. The bar 25 is then positioned above the semi-circular recesses in the arms 21, 24 and lowered until it rests upon the arms 23, 24. Thereafter, the lifting means is disconnected, or sufficient slack introduced therein, and the motor 29 started.

It is believed that the invention will now be clearly apparent from the above description of the present preferred embodiment.

Variations, however, may be effected in the disclosed apparatus. For example, the rocking of the arms 23 and 24 need not be effected by employing a reversible electric motor together with the circuit herein illustrated and described but may be effected by a unidirectional power means connected with the shaft 11 by a suitable eccentric or crank arm.

The abutments 89 and 90 may also be varied from those shown in the drawing. The operation is not changed if the abutment 90 be higher than the abutment 89 nor, in fact, is it necessary that these abutments be of different heights since they may be of the same height but disposed with their inner edges at different distances from the vertical diameter of the coils to be treated. Moreover, the circumferential displacement of the convolutions of the coils and/or partial rotation of the coils may be effected by surfaces other than the substantially rectangular abutments illustrated, as for example, by employing irregular surfaces of other configurations, which may be supported either on the bottom of the tank or spaced therefrom. In addition, the hook 26 may be replaced by other types of supporting members.

These and other modifications which may be effected by those skilled in the art are considered as comprehended within this invention and hence the latter is to be considered as limited only as required by the spirit and scope of the appended claims.

Having thus described my invention, I claim:

1. An apparatus for pickling loosely coiled metallic strip material comprising, a tank adapted to contain a pickling solution, a pair of spaced abutments in the bottom of said tank and supported therein, a supporting member adapted to engage the inner convolution of a coil of the material to be treated within said tank, and means to repeatedly raise and lower said supporting member within said tank so that the weight of the coil is alternately supported by said supporting member and by said spaced abutments; said abutments being of such size and so spaced that the coil engages the one of said abutments in advance of the other during the descent of the

coil within the tank thereby effecting partial rotation of the coil, and the said means for raising and lowering the supporting member including adjustable means settable to control the extent of movement of said supporting member relative to the said abutments.

2. An apparatus for pickling loosely coiled metallic strip material comprising a tank adapted to contain a pickling solution, supporting means adapted to engage the inner convolution of a coil to be pickled and support the coil suspended in said solution, a pair of spaced abutments in and supported by said tank for engaging and supporting the outer convolution of said coil, and means for raising and lowering said supporting means so that the weight of said coil is alternately supported by and relieved from said supporting means and said abutments thereby radially moving the inner convolutions of the coil relative to the outer convolutions, the spacing of said abutments being such that the coil engages one of the abutments to one side of the vertical diameter of the coil in advance of its engagement with the other of said abutments so that the weight of the coil effects a partial rotation thereof between each alternate raising and lowering of said supporting means, and the said means for raising and lowering the supporting means including a reversible power means, adjustable means responsive to the extent of movement of said supporting means in either direction for effecting reversal of said power means, the said adjustable means being settable to provide different extents of movement of said supporting means relative to said abutments.

3. An apparatus for pickling loosely coiled metallic strip material comprising an elongated tank adapted to contain a pickling solution, a pair of spaced abutments in the bottom of said tank and supported thereby, a supporting member adapted to engage the inner convolution of

a coil of material to be treated, a shaft extending longitudinally along one side of said tank, a plurality of arms connected to said shaft and projecting inwardly of said tank so as to overhang said tank, means for connecting said supporting member to said arms, and means for oscillating or rocking said shaft whereby the projecting ends of said arms overhang said tank and in turn said supporting member are repeatedly raised and lowered so that the weight of the coil is alternately carried by said supporting member and by said spaced abutments, said abutments being of such size and so spaced that the coil engages one of said abutments in advance of the other during its descent within the tank thereby effecting partial rotation of the coil, and the said means for oscillating said shaft including a reversible electric motor connected to the shaft, electrical switch means connected with said motor to sequentially effect rotation thereof alternately in opposite directions, and adjustable means movable in timed relationship with the said supporting member engageable with said switch means for alternate actuation thereof, the said adjustable means being settable to provide different extents of movement of said supporting member between actuations of the said switch means thereby controlling the extent of movement of the said member relative to the said abutments.
